(57) **CLAIM**

We claim the ornamental design for an extendible camera handle, as shown and described.

DESCRIPTION

FIG. 1 is a bottom perspective view of an extendible camera handle, showing a first embodiment of our new design in an retracted configuration;

FIG. 2 is a front perspective view of FIG. 1;

FIG. 3 is a rear perspective view of FIG. 1;

FIG. 4 is a left-side devotional view of FIG. 1;

FIG. 5 is a right-side elevational view of FIG. 1;

FIG. 6 is a front elevational view of FIG. 1;

FIG. 7 is a rear elevational view of FIG. 1;

FIG. 8 is a top plan view of FIG. 1;

FIG. 9 is a bottom plan view of FIG. 1; and,

FIG. 10 is a perspective view of the first embodiment in an extended configuration.

The broken lines in the figures showing a head mechanism and chain depict environmental matter and form no part of the claimed design.
